PLURAL FIRE ALARM SIGNALING SYSTEM
REPRODUCING SOUND RECORDSKeith Lansing Bell, Washington, D. C., assignor
of one-half to Curtis E. McGhee, Washington,
D. C.

Application February 3, 1941, Serial No. 377,253

8 Claims. (Cl. 177—360)

This invention relates to signaling apparatus generally. More particularly this invention relates to signaling apparatus such as fire alarms in which a recording is reproduced for the purpose of giving the fire alarm.

An object of this invention is to provide fire alarm signaling apparatus in which recorded signals are reproduced for the purpose of giving a fire alarm.

Another object of this invention is to provide signaling apparatus employing a plurality of signal records, each of said records having means associated therewith whereby selected ones of said records may be reproduced as desired.

A further object of this invention is to provide a plurality of signal records and common reproducing means associated therewith for selectively reproducing said records.

Another object of this invention is to provide one or more signal records in a street fire alarm box, said street fire alarm box having a low-powered radio transmitting device associated therewith for transmitting the fire alarm signal to desired fire fighting apparatus when said box is actuated.

Still another object of this invention is to provide fire alarm signaling apparatus for heavily populated sections, said signaling apparatus having means provided thereto for selectively signaling for large fires and small fires.

Other and further objects of this invention will be apparent to those skilled in the art to which it relates, from the following specification and the claims.

In accordance with this invention I provide a signaling system for use in signaling fire alarms, said signaling system being adapted to save considerable time in transmitting the alarm from the fire to the fire apparatus station. In addition to saving time in signaling, my invention also is provided with means for transmitting different signals for a large fire from those transmitted for a small fire. This is extremely important in fighting fires in relatively heavily populated sections. The system now in use does not distinguish between large and small fires and as a result as an alarm comes into the fire apparatus station from a relatively heavily populated center usually all or a large part of the fire apparatus responds to that fire.

On many occasions it is found that the fire could have been put out by one piece of fire fighting apparatus and the wear and tear on the other apparatus could thus have been saved. However in the system now in use no way of

transmitting a signal characterised by the size and danger of the fire is provided and consequently the fire department must respond with what it considers sufficient apparatus and this usually depends upon the density of the population in the section where the fire occurred. Consequently much more fire fighting apparatus is required because a sufficient reserve must be kept at the fire station to take care of more than one alarm. In my system it is not necessary for large forces of apparatus to respond unless the "large fire" signal is given and as a result the other apparatus may be kept in reserve.

15 In this invention I provide an arrangement whereby one or more records and record reproducing devices are housed in a substantially sound-proof street fire alarm box. The recordings preferably consist of sound records which 20 may be in the form of recordings of sound vibrations on disk tablets, cylinders or the like, or they may be sound recordings on film such as used in talking motion pictures, or they may be magnetic recordings on magnetic tape, wire, 25 disks or cylinders. Slow speed recordings, such as, for example, recordings corresponding to 33 R. P. M. are preferably employed although of course various other speeds may be used if convenient. The record reproducing device or 30 devices used in the street fire alarm box are connected to a cable leading to the fire apparatus station where the signals are amplified and reproduced through a suitable loudspeaker as well as recorded for future reference. A small amplifier may be provided in a street fire alarm box for amplifying the signal reproduced from the recording before this signal is transmitted over the cable to the fire apparatus station; however this is not necessary.

35 Furthermore, if desired, the record reproducing devices at the street fire alarm box may be used to modulate a relatively low-powered radio transmitting station which may be of the ultra-high-frequency type. In this way signals may be 40 transmitted from the street fire alarm box directly to a fire-fighting truck, scout car and/or to the fire apparatus station. Each street fire alarm box radio transmitter may be assigned a slightly different carrier frequency, or if a large 45 number of fire alarm boxes use the same carrier frequency, they may be distinguished by different modulating frequencies.

50 For example the carrier frequency of one radio transmitting station may be modulated with a constant tone frequency of 10 kilocycles and the

recording signals used to modulate this 10 kilocycle frequency. Another street box station may have its carrier modulated with a 19 kilocycle frequency which is modulated by its recording signals and so on. This may be readily accomplished when ultra-high frequency radio signals are employed. These signals have a relatively limited effective range and if low power is employed no danger of interference between neighboring cities would be encountered.

Furthermore the record reproducing devices of one street box may be joined to the record reproducing devices of another street box through a co-axial cable which in turn is connected to the fire apparatus station. In this case the recordings of one street fire alarm box may be made by super-imposing the recorded sounds upon a relatively high frequency carrier sound, so that the records reproduced at one street box differ from those reproduced at another street box because different high-frequency carrier sounds are used in making the recordings for the different boxes. Thus the operator at the fire apparatus station will know immediately from which street box he is receiving signals. This type of recording also may be used in modulating the ultra-high-frequency transmitter and the modulating problem thereby simplified.

Other features of this invention will be apparent to those skilled in the art to which it relates, from the following specification, claims and drawings in which briefly:

Fig. 1 illustrates a schematic diagram of connections of the apparatus of my invention;

Fig. 2 is a view of the front face of a fire alarm street box;

Fig. 3 illustrates a form of recording employed in accordance with this invention, having the messages of the various successive alarms recorded in sequence on the disk;

Fig. 4 shows a modified form of sound track pick-up device;

Fig. 5 illustrates a magnetic record carrying device employed in accordance with this invention;

Fig. 6 illustrates a sound on film record; and

Fig. 7 is a detailed view of a switch illustrated schematically in Fig. 3.

Fig. 8 shows a combined assembly of the automatic and manual switches and their controls of Fig. 7, mounted for cooperative actuation with the plural alarm record disk of Fig. 3.

Referring to Fig. 1 of the drawings in detail, reference numerals 10, 11, 12, 13, 14 and 15 designate circular sound record bearing elements having associated therewith styli 20, 21, 22, 23, 24 and 25 respectively, for reproducing the signals recorded thereon. Each of the elements 10, 11, 12, 13, 14, 15, is provided with a portion as 10-b having a locking notch 162; this is shown in Fig. 1 only for the first element 10. The styli may be of any conventional type made of materials such as steel, fiber, sapphire and the like, and the record carrying members 10 to 15 inclusive also may be of conventional materials such as shellac and compositions thereof, hard rubber, synthetic resin, Celluloid, cellulose acetate, aluminum, anodized aluminum and the like. Each of the styli 20 to 25 inclusive are attached to a suitable armature which is positioned in the magnetic field of a suitable coil 30 to 35 inclusive, respectively.

Where desired the styli 20 to 25 inclusive may be attached in a conventional manner to a piezo-

electric crystal pick-up and in that case the crystal is substituted for the coils 30 to 35 inclusive.

The record bearing members 10 to 15 inclusive are attached to spring motors 40 to 45 inclusive, respectively, and these spring motors are provided with suitable driving means for driving the record carrying members associated therewith at a substantially constant speed when the aforesaid record carrier members are released by the manually operable hooks 50 to 55 inclusive. The hooks 50 to 55 inclusive are provided with catch elements 60 to 65 inclusive, respectively, which engage suitable notches 162 formed in the portion as 10-b of record elements 10 to 15 inclusive, respectively. Thus when the hook 50, for example, is pulled down, the catch 60 releases the record element 10 and the spring motor 40 rotates this record element. The catch 60 rides on the unnotched part of the periphery of portion 10-b of member 10, and is held depressed and holds switch 80 closed until member 10 rotates a revolution to again bring notch 162 to engage catch 60. As a result the stylus 20 reproduces the record carried by the element 10. In the same manner the other record elements may be released by pulling down the hooks associated therewith.

In practice the element 10 has inscribed thereon the first alarm and the hook 50 may therefore be actuated from the outside of the box 56 shown in Fig. 2 for transmission of the first alarm from the scene of the fire. In order to transmit second, third, fourth and fifth alarms, the box 56 must be opened and the hooks 51, 52, 53 and 54 operated from the inside thereof. A second hook 55 also may be operated from the outside of the box and this hook is employed for the purpose of releasing the small fire signal record 15. A small crank 46 is provided on each of the spring motors 40 to 45 inclusive for the purpose of winding these motors.

Suitable switches 80 to 85 inclusive, mechanically coupled to the hooks 50 to 55 inclusive, respectively, are provided in series with the pick-up coils 30 to 35 inclusive, respectively. These switches are each arranged so that pulling downwardly the hook associated therewith closes the circuit of the corresponding switch. For example, pulling the hook 50 down releases the record element 10 and at the same time closes the switch 80. Each of the hooks 50 to 55 inclusive is provided with a bias spring 70 to 75 inclusive, respectively, tending to maintain the hook associated therewith in its upper position.

The pick-up coils 30 to 35 inclusive may be connected directly to the cable 108-109 which may be a conventional two-wire cable or a co-axial type cable as 109-a. On the other hand, if it is desired to tune each of the pick-up coils 30 to 35 inclusive to a somewhat different audio or supersonic frequency, condensers 90 to 95 inclusive of sizes such as to tune each of the coils to different frequencies, may be connected in series therewith. In the circuit shown, a suitable vacuum tube amplifier 106 is shown as connected between the pick-ups 30 to 35 inclusive and the cable 108-109, and this amplifier is shown as a common amplifier for all of the pick-ups. In known manner there may be alternatively employed individual amplifiers for the individual pick-ups, or individual amplifiers for the individual pick-ups connected to a common power amplifier the output of which is in turn connected to the cables 108-109.

It is of course desirable to match the impedance of the pick-ups 30 to 35 inclusive, individually to the cable 100-109, and for this purpose suitable impedance matching networks may be provided between these pick-ups and the cable.

Where desired the amplifier 106 may be provided with a suitable antenna 107 and radio frequency generator 151 for the purpose of radio transmission. This radio transmission may take place simultaneously with that over the cables 108-109 or independently of the cable transmission. For this purpose the antenna 107 may be a dipole type as shown in Fig. 2 supported on the box 56 by means of a substantially rigid co-axial cable 110 which enters the box through the insulator 111.

Where desired the record elements 10, 11, 12, 13 and 14 may be combined into one unit 10a as shown in Fig. 3 and Fig. 8, and in this case the record of the element 10 is inscribed on the record 10a between the notches 120 and 121. The record corresponding to the element 11 is inscribed between the notches 120 and 124 and that of elements 12, 13 and 14 between the notches 124-123, 123-122, 122-121, respectively.

Thus when the record element 10a is released by pulling down the hook 50a against its spring, the stylus 20a reproduces the first alarm until the hook 50a engages the notch 124. In order to signal the second alarm, the hook 50a must be pulled again to release the element 10a further. However the switch 80b in shunt with switch 80a must be manually closed before the second alarm may be transmitted since the hook 50a is arranged to close the switch 80-a only for the first alarm.

This is shown more clearly in Fig. 7 and Fig. 8. In these figures are illustrated a contact plunger 126 of insulating material which is provided with a pawl and ratchet device 127-128 on the side thereof, and is normally held up by spring 166. The plunger 126 is connected mechanically to the hook 50a by connecting rod 130 and catch rod 175-131, and when this hook 50-a is pulled down the plunger 126 is also pulled down so that the contact stud 80-c carried by plunger 126 and both of the fixed contacts 80a are in line and the circuit of the electric pick-up 30a is closed to amplifier 170 and co-axial cable 171. This circuit remains closed because the catch 128 engages the bottom tooth 127 and holds the contact stud 80-c in line with fixed contacts 80-a.

When the hook 50a is pulled the second, third, fourth and fifth times, that is, to release the element 10a respectively from notches 124, 123, 122, 121, the catch 128 is caused to engage the upper tooth 127 and hold the contacts 80a out of line. Consequently the manual auxiliary switch 80b which short-circuits the contacts 80a must be closed manually before the second alarm can be transmitted and this should preferably be done by a fireman. The connecting rod member 130 and catch rod 175 connect the plunger 126 to the hook 50a, and the latter is provided with a catch 131 similar to catch 128 and the actuating rod 129 of hook 50a is provided with teeth 132 to engage the catch 131. However the rod 129 has three teeth 132 whereas the plunger 126 has only two teeth 127 inasmuch as the catch 131 is initially in engagement with the uppermost tooth 132. The switch 80b is automatically opened by the projection 125 of the plural-record-bearing element 10a when this element completes a cycle of operation, that is, when the element 10a is

completely rotated, by projection 125 engaging terminal block 172 of control rod 169, and overcoming its spring, and pin 173 is pushed down to open switch 80-b. At the same time the 5 catches 128 and 131 are also automatically released by the projection 125 pushing control rod 169 down and causing bell cranks 174 and 173 to respectively push back rod 180 carrying catch 128, and rod 175 carrying catch 131, by pushing 10 on pin 179, so that the hook 50a and plunger 126 may return to their normal stopped position at which the hook 50a is in the notch 120, and the box is re-set for another cycle of operation.

If after arriving at a fire, the fireman finds it 15 only a one-alarm fire and that there is no need of a second or further alarm, the fireman opens the box and manually releases the record bearing disc 19-a and rotates the same until its first alarm sector carrying the projection 125 is in 20 actuatable position as shown in Fig. 3. As this is being done, the projection 125 engages cam 172 and thereby disengages the catch 128 and the catch 131 from their respective teeth on rods 126 and 129 which re-sets rods 126 and 129. The 25 catches 128 and 131 may also be individually released manually if desired by the fireman when the box is open.

In Fig. 4 I have illustrated a form of this invention in which the record reproducing stylus 20 to 25 inclusive are mounted on a common member 126a which is connected to the armature of the pick-up coil 30b. Suitable springs 163 are employed for supporting the member 126a.

Fig. 5 shows a form of this invention employing a magnetic tape or wire 147 for carrying the record of the desired message, and running between reels 164, 164. A reproducing pick-up device 148 is positioned adjacent to the magnetic tape 147 for reproducing the record from this tape. A suitable amplifier 149 or other device such as the apparatus 106 shown in Fig. 1, is connected to the pick-up device 148. An erasing magnet 143 is provided adjacent to the tape 147 for the purpose of erasing the magnetic recording 45 on the tape if desired. Another magnet 150 used to place a magnetic record on the tape is provided and this magnet is connected to the amplifier 151 and the microphone 152. The microphone 152 and amplifier 151 need not be positioned in the box but may be disconnected therefrom and connected thereto by a fireman desiring to put a new message on the magnetic tape 147.

Fig. 6 illustrates another form of this invention employing a disk 134 having a record thereon 55 adapted to modulate the light from the lamp 137 and lens 136 before said light passes to the light sensitive cell 135. The light sensitive cell 135 may be a selenium cell, a photovoltaic cell, an alkali photoelectric cell or similar light responsive device. In this case the manual control hook 50b engages a gear inside of the spring motor 40a to release and stop the rotation of the disk 134 by the spring motor.

It is obvious that various messages may be 65 placed on the record elements in the street fire alarm box. For example the identity of the box may be carried by these record elements in the form of voice or sound recordings. The street on which the box is located also may be carried by the sound record element. Various other information may be inscribed on these records for the purpose of assisting the fire department. A suitable amplifier is provided at the central fire station for amplifying the messages received 70 from the various fire boxes. This amplifier also

may be connected to recording apparatus for recording the messages received from the fire boxes.

What I claim is:

1. Fire alarm signaling apparatus of the class described, comprising: a recording containing a plurality of fire alarm messages desired to be transmitted selectively, an electrical device for reproducing said recording, a housing for said recording and said electrical device, a manual fire alarm release device extending to the outside of said housing for initiating the reproduction of said recorded fire alarm message, means for transmitting the fire alarm message to at least one fire apparatus station, a switch mechanically connected to said manual release for connecting said electrical device to said last means, means for opening said switch when the first message of said recording is reproduced, and an auxiliary manually operated switch for closing the circuit to said electrical device for the reproduction of additional messages from said recording the transmission of the second, and third alarms.

2. Fire alarm signaling apparatus as set forth in claim 1 further characterized in that said manual release consists of a hook, an insulating member mechanically connected to said hook for carrying contacts of said first switch for closing the circuit of said electrical device when said hook is operated for transmitting the first alarm.

3. Fire alarm apparatus as set forth in claim 1 further characterized in that said recording consists of a member having catches for determining the movement thereof in the reproduction of each of the alarms.

4. Fire alarm apparatus as set forth in claim 1 further characterized in that said manual release consists of a hook, an insulating member mechanically connected to said hook for carrying contacts of said first switch for closing the circuit of said electrical device when said hook is operated for transmitting the first alarm, and a mechanical release associated with said recording for releasing all of said switches and said hook after a predetermined alarm has been transmitted.

5. In fire alarm signaling apparatus, a disc peripherally provided with a plurality of engaging means, the sectors between said peripheral engaging means being provided consecutively with a series of separate recorded messages respectively designating consecutive fire alarms from a first alarm to a plural numbered alarm, electrical pick-up means adapted to translate said recorded messages into electrical energy, means for rotatably driving said disc, displaceable locking means adapted when displaced to selectively lock said disc into fixed position or release said disc for free rotation, an electrical output circuit connected to said electrical pick-up means and comprising a serially connected principal switch, means interconnecting said locking means and said switch and adapted to hold said switch closed when said locking means is in free released position and to leave said

switch open when said locking means is in locking position whereby a first alarm may be sent in when said switch is closed, and means whereby a plural numbered alarm may thereafter be sent independent of the position of said switch.

6. Apparatus according to claim 5, and resilient means normally urging said switch into an open position, and retaining means adapted to retain said switch in closed position when displaced thereto by displacement of said locking means.

7. Apparatus according to claim 5, said displaceable locking means being provided with a locking rack, said interconnecting means comprising an engaging finger adapted to engage a tooth of said locking rack, and said switch being longitudinally displaceable into and out of closed position and comprising a second rack, resilient means urging said switch in one direction, and a switch catch adapted to engage a tooth of said second rack for holding the same in a fixed position against the urging of said resilient means, and said switch and said locking means and said interconnecting means being so constructed and arranged that the first actuation of said locking means displaces said switch into and retains the same in closed position, and the second actuation of said locking means displaces said switch into and retains the same in open position until said catch is released from engagement with said second rack.

8. Apparatus according to claim 5, said displaceable locking means being provided with a locking rack, said interconnecting means comprising an engaging finger adapted to engage a tooth of said locking rack, and said switch being longitudinally displaceable into and out of closed position and comprising a second rack, resilient means urging said switch in one direction, a switch catch adapted to engage a tooth of said second rack for holding the same in a fixed position against the urging of said resilient means, and said switch and said locking means and said interconnecting means being so constructed and arranged that the first actuation of said locking means displaces said switch into and retains the same in closed position, and the second actuation of said locking means displaces said switch into and retains the same in open position until said catch is released from engagement with said second rack, said plural numbered alarm sending means comprising a manually actuatable auxiliary switch connected in parallel with said principal switch, said disc comprising a peripheral cam member positioned adjacent the beginning of the first alarm of said series of messages, cam engaging means engageable with said cam member, and interlocking means actuatable by said cam engaging means and adapted to open said auxiliary switch and release said engaging finger and said switch catch from engagement with their respective racks, for re-setting said apparatus for a new operating cycle beginning with said first alarm.
